UNITED STATES PATENT OFFICE.

JOHN STOGDELL STOKES, OF MOORESTOWN, NEW JERSEY, ASSIGNOR TO STOKES & SMITH COMPANY, OF SUMMERDALE, PHILADELPHIA, PENNSYLVANIA, A CORPORATION OF PENNSYLVANIA.

CONTAINER STRUCTURE.

1,425,714.

Specification of Letters Patent. Patented Aug. 15, 1922.

Application filed April 3, 1918. Serial No. 226,429.

To all whom it may concern:

Be it known that JOHN STOGDELL STOKES, a citizen of the United States, residing at Moorestown, in the county of Burlington and State of New Jersey, has invented new and useful Improvements in Container Structures, of which the following is a specification.

This invention relates to container structures which may be in the form of complete containers or of shells, the latter being generally formed with the top (or bottom) permanently open, the container, in such case, being produced by telescoping two mating shells.

The present invention is designed more particularly for the production of container structures from paper stock somewhat pliable in character—a stock of materially lighter weight than is generally employed in container production.

Obviously container structures for commercial use should be of sufficient stiffness to substantially retain the shapes which they are designed to have. Heretofore, this has been provided to a great extent by the stiffness of the material itself, the folding being designed more particularly to produce the desired shape. Where, however, the material is more or less pliable, the resistance must be provided in other ways, as, for instance, by the manner of folding or the manner in which the parts are secured in their shaped positions.

In forming shells, this result is generally had by a composite formation—a stiff board body and a flexible wrapper—requiring the use of two blanks and more or less separate folding operations. In container structures, a single blank has been employed—as for instance is the case with collapsible containers—but these are more or less complicated in structure and are not produced in set-up formation, setting-up being by hand labor, excepting in few instances where the character of the container blank is complicated and requires the use of complicated special machines for the production; thus involving

large investments in machines usable only for the specific purpose.

Obviously, the successful structure for commercial use should be capable of production under large capacity conditions and at minimum cost of production, and hence the problems presented in producing structures from pliable material not only involve the use of special formations to meet the conditions of service of the container or shell, but also the problem of providing the formations in such manner as to permit rapid production by standard machines, since the commercial requirements of containers of this general type does not generally warrant the investment required for machines adapted for use only for the single purpose.

The present invention is designed more particularly to meet these problems by the use of a general form of blank or blanks which are foldable and adhesively secured in such manner as to give the necessary and desired stiffness when using stock having more or less pliable characteristics, thus enabling the container structure to be formed from a single blank to produce a light weight structure, and at the same time produce a blank formation capable of being manipulated into container formation on standard machines adapted for production of other types of containers or shells with little or no change in the machine structure, and which are adapted to produce containers or shells differing in size, etc.

To these and other ends, therefore, the nature of which will be readily understood as the invention is hereinafter disclosed, said invention consists in the improved construction and combination of parts herein-after fully described, illustrated in the accompanying drawings, and more particularly pointed out in the appended claim.

In the accompanying drawings, in which similar reference characters indicate similar parts in each of the views:

Fig. 1 is a perspective view showing a general form of blank adapted to be formed

into a container structure having an integral closure.

Fig. 2 is a perspective view showing the blank folded with the closure in open position.

Fig. 3 is a similar view with the closure in closed position.

Fig. 4 is a detail sectional view taken on line 4—4 of Fig. 2.

Fig. 5 is a perspective view of a blank adapted for formation of a shell.

Fig. 6 is a perspective view of a shell formed from the blank of Fig. 5.

Fig. 7 is a detail sectional view taken on line 7—7 of Fig. 6.

As will be understood the sizes of parts and thickness of the paper stock, as shown in the drawings are simply illustrative.

In the present invention the stiffness of the container or shell is provided by the particular manner in which the various portions of the blank are folded and adhesively connected and reinforced. This is provided in a simple and efficient way—readily adapted for production on standard machines—and serves to so stiffen the container structure as to materially reduce the necessity of relying on the paper stock for material aid in stiffening the structure. As a result, the structure can be produced from a single blank and, in addition, this blank can be formed from paper stock materially lighter in weight as compared with prior structures, a stock which may have pliability characteristics, and which may, if desired, preponderate in the characteristic of toughness rather than stiffness.

Figs. 1 to 3 indicate more particularly the arrangement where the product is in the form of a one-piece container, Figs. 4 and 7 indicating sections common in both forms of container structures.

The container of Figs. 2 and 3 is formed from a blank shown more particularly in Fig. 1, in which 10, 11 and 12 indicate, respectively, the front, bottom and rear wall sections, 13 indicating the closure section. As shown, section 10 has narrow integral flaps 10^a extending from its ends and a flap 10^b extending from its outer or side edge; section 11 has end wings 11^a; the main portions of which are of the same area as the ends of the completed box or carton, and these end wings have on their outer edges narrow flaps 11^b. Section 12 has end flaps 12^a similar to flaps 10^a. The flaps 10^a and 12^a provide corner reinforcements and the flaps 10^b and 11^b provide edge or marginal reinforcements in the completed box or carton, as later more particularly described.

As will be seen, marginal flaps 10^b and 11^b are each given an adhesive coating, and in addition, each wing 11^a is provided with zones of adhesive 11^c and 11^d, extending along its opposite side edges and a zone 11^e

extending along that portion adjacent to flap 11^b may also be provided.

The blank may be scored on the lines indicated or the folding may be had without previous scoring, the folding machine being designed to produce the proper folding.

Folding of the blank is by raising sections 10 and 12 perpendicular to section 11—section 13 moving with section 12. This places flaps 10^a and 12^a facing each other. These flaps 10^a and 12^a are then turned inward into alignment with each other, after which wings 11^a are raised, adhesive zones 11^c and 11^d being brought into contact with the outer faces of flaps 10^a and 12^a respectively, and adhesively applied thereto. Flaps 10^a and 11^b are then infolded to reinforce the upper edges of the container body thus formed. Flaps 11^b preferably overlie wings 10^a and 12^a, thus locating the latter between wings 11^a and flaps 11^b and strengthening the end construction.

As will be seen, the vertically-extending corners of the body are of two-ply thickness, these plies extending inward from directions 90 at right angles to each other; these plies, being adhesively connected, will stiffen the body portion against collapse provided by pressure applied in directions transverse to the length of the body, the integral connection of wings 11^a with section 11, and the right-angle bend therebetween, serving to brace the bottom, while the infolding of flaps 11^b forms a folded reinforce at the top of the ends.

Stiffness in the direction of length of the body is had through infolding flap 10^b at the front and the integral connection of sections 12 and 13 together with the right-angle bend therebetween.

Stiffening at these points will offer sufficient resistance against collapse to permit the use of paper stock of lighter weight and which may have characteristics of pliability and toughness.

Section 13 is provided with flaps 13^a and 13^b, these being designed to extend into the container when section 13 is moved to closing position.

In some cases in producing the shell formation, as shown in Fig. 5, section 13 and its flaps are omitted, a flap 12^b being utilized, this flap being adhesively coated and serving a purpose similar to flap 10^b, thus providing an inturned reinforcing element 120 along the top of each of the four sides of the open-top container structure or shell.

As will be understood, the particular manner in which the end formations are provided, and the presence of the reinforcing flaps, provides the desired stiffness at the needed points, so that less dependence need be placed on the character of the stock to provide stiffness. As a result, stock, more or less pliable in character, and of lighter

weight, may be employed, thus not only decreasing cost of material, but decreasing the weight of the package accordingly. And since the structure is one which can be readily produced on standard machines, the cost of production is also materially reduced over the general cost of manufacture of container structures of usual character. This decrease in cost of manufacture not only permits of expansion of the use of such structures in the present fields, but makes possible the use of pre-formed container structures in fields heretofore limited to ordinary wrapping service, the small increased cost being more than overcome by the superiority in the form of the package produced.

As will be understood, the particular sizes of parts shown in the drawings is more or less illustrative. The particular structure herein disclosed is capable of being manufactured in comparatively large sizes, the structural formation being such as to permit this to be done even when paper stock of pliable characteristics is employed. Hence, the ability to produce these structures on standard machine—adapted to operate in connection with structures of various sizes—becomes of importance, since one machine may serve to produce container structures of different sizes and thereby dispense with the necessity for providing complicated special machines which are designed and used only in the production of containers of a single type and size.

While I have herein shown and described

several ways in which the invention may be carried out, it will be readily understood that changes and modifications therein may be found desirable or necessary in meeting the exigencies of use, and I desire to be understood as reserving the right to make any and all such changes or modifications as may be found desirable or essential in so far as the same may fall within the spirit and scope of the invention as expressed in the accompanying claim.

What I claim is:

A container or box part consisting of a single sheet of relatively thin and flexible paper having in itself insufficient stability for the designated service, said sheet being cut into a blank having a bottom section and integral front and rear wall sections and end wing sections, narrow margin-reinforcing flaps extending from free edges of the end wing and wall sections and narrow corner-reinforcing flaps extending from other free edges of said sections, the blank being folded into box form with said corner-reinforcing flaps adhesively secured to marginal portions of adjacent sections and with said margin-reinforcing flaps turned down and adhesively secured to marginal portions of the respective sections providing integral corner and margin-reinforcements imparting sufficient stability for container use.

In testimony whereof I have hereunto set my hand.

JOHN STOGDELL STOKES.
